UNITED STATES PATENT OFFICE.

RICHARD SCHEIBEL, OF ST. LOUIS, MISSOURI.

ARTIFICIAL LIMB.

1,265,965.

Specification of Letters Patent.

Patented May 14, 1918.

Application filed June 12, 1916. Serial No. 103,295.

To all whom it may concern:

Be it known that I, RICHARD SCHEIBEL, a citizen of the United States, and resident of St. Louis, Missouri, have invented certain new and useful Improvements in Artificial Limbs, of which the following is a specification.

This invention relates to improvements in limb sockets, and has for its object a hollow structure formed of a plurality of spirally wound strips of fabric which have been previously saturated in an adhesive material such as glue or the like, and then being coated with a water-proof coating.

15 A further object is to make a limb socket which will be light in weight and at the same time strong enough to bear the weight of the wearer.

20 A further object is to construct a limb socket which does not require the services of an expert in carving which is now necessary in the manufacture of limbs made of wood or similar substance.

Figure 1, is a vertical sectional view of 25 my complete invention.

Fig. 2, is a front view of the same with the outer coverings removed.

Fig. 3, is an enlarged detail horizontal sectional view through a portion of the wall 30 showing the several layers of material used in the construction of my device.

In carrying out my invention I use a mold of any desired construction either formed 35 sectional or of some material which may be later on destroyed; and over this I place a covering A of paper which is water-proofed or other similar substance. Over this layer 40 of paper I draw a footless stocking B which has been previously saturated in some moisture proof adhesive substance. When this adhesive substance has partially set I wind a layer of muslin or like material, which has also been previously saturated with a like 45 substance, spirally about the stocking; this layer being designated by the letter C. Then saturated layers of like material D, E, F, G, and H are wound spirally about the layer C in alternate directions; this is continued until the desired thickness or strength 50 has been reached which depends entirely

upon the weight of the party wearing the limb. After sufficient material has been wound around the mold I next draw a stocking I, also saturated with adhesive material, over the spirally wound strips and when the 55 entire mass has sufficiently dried out I cover the same with a coating J, composed of chalk and glue to fill up any spaces or irregularities which might have been left by the winding. When this coating is hardened it 60 is sand-papered or smoothed down and then given a coat of flesh tinted shellac or varnish so as to keep the moisture from attacking it from the outside.

By my structure I provide a device which 65 is very light, rigid vertically and at the same time resilient to lateral pressure making it seem very much like the ordinary limb which is composed of flesh and bone.

After this device is completed I attach a 70 foot member 19 to the lower end thereof, in the upper end I provide a socket 20, in which is located a member 21, the same being hinged by the pivot 22, located in the leg member. The upper end of the section 21, 75 being secured in the member 23, which is constructed exactly the same as has been previously described.

It is understood of course that if the limb is taken off below the knee the sections 20, 80 21, 23, and the pivot 22, will not be needed.

Having fully described my invention what I claim is:

A leg socket having an interior lining of moisture proof material, a stocking, spirally 85 wound layers of muslin saturated with adhesive material wound over the same, a second stocking, a coating formed of chalk and glue applied over the stocking and a tinted moisture proof coating applied over 90 the mixture of chalk and glue, substantially as specified.

In testimony whereof, I have signed my name to this specification, in presence of two subscribing witnesses.

RICHARD SCHEIBEL.
